HOE

Filed Nov. 30, 1923

Inventor
A. B. GARRETT

Attorney

UNITED STATES PATENT OFFICE.

AMOS B. GARRETT, OF TYLER WOODS, PENNSYLVANIA.

HOE.

Application filed November 30, 1923. Serial No. 677,924.

The present invention relates to a hoe particularly adapted for use in cleaning out pipes which run underneath and adjacent to roadways for drainage purposes. With the ordinary hoe it is very difficult to clean out these pipes and often quite impossible, necessitating the removal of the pipes at a considerable expense and to the detriment of the roads. The present invention provides a device which will efficiently clean out such pipes and save considerable labor and expense.

An important object of the invention is to provide a hoe of this nature having a simple construction, one which is reliable in operation, inexpensive to manufacture, durable, and well adapted to the purpose for which it is designed.

With the above and numerous other objects in view as will appear as the description progresses, the invention resides in certain novel features of construction, and in the combination and arrangement of parts as will be hereinafter more fully described and claimed.

In the drawing:

Figure 1 is a side elevation of the hoe embodying my invention,

Figure 2 is a top plan thereof,

Figure 3 is a detail perspective of the blade of the hoe, and

Figure 4 is a transverse section taken substantially on the line 4—4 of Figure 1 looking in the direction of the arrow.

Referring to the drawing in detail it will be seen that the hoe includes a bar 1 which may be of the desired length and terminates at one end in a right angled extension 2 forming a handle and at its other end in a pair of spaced apertured ears 3. A blade 4 is provided at one end with an apertured lug 5 fitting between the apertured ears 3 so that a pin may be passed through the lug and the ears for hinging this blade to the end of the bar. The outer or free edge of the blade is semi-circular in formation as is indicated at 5 so that the blade may be efficient in scraping pipes and the like. A block 6 is fixed to the bar 1 adjacent the end to which is hinged the blade 4 and a leg 7 depends therefrom terminating in a foot 8.

A plurality of eyes 9 are formed on the bar 1 for receiving a rod 10 which is slidably through the eyes and through an aper-

ture provided in the block 6. The end 11 of this rod is offset and is pivotally connected with an intermediate portion of a lever 12 which is fulcrumed at one end to the bar 1 adjacent the extension 2. This rod 10 is adapted to be operated by the lever 12 and is formed of metal and will give sufficiently to accommodate the circular movement of the lever 12. The outer end of the rod 10 terminates in an eye 13. Links 14 are connected to the eye 13 and also to eyes 15 provided on the blade 4. Thus it will be seen that by operation of the lever 12 through the intermediacy of rod 10 and links 14 the blade may be swung to different angles in relation to the bar 1.

In actual use the blade 4 is held in the position shown in Figure 1 and inserted into the pipe, the foot 8 of the leg 7 resting on the bottom thereof. The hoe is then shoved into the pipe as far as desired and the lever 12 actuated to swing the blade at approximately right angles to the bar. The hoe may then be pulled out of the pipe and of course will clean the same of whatever dirt may be therein.

The device is also useful in numerous other connections and is susceptible of changes in construction and in the combination and arrangement of parts without departing from the spirit of the invention as hereinafter claimed.

Having thus described my invention what I claim as new is:

1. In a hoe of the class described, a bar, a blade hinged to one end of the bar, a rod, means for slidably mounting the rod alongside of the bar, links at one end of the rod, said links being connected to the blade, and a lever pivoted at one end to the bar and intermediate its ends to the rod all in the manner and for the purpose specified.

2. A hoe of the class described comprising a bar, a blade hinged to one end of the bar, a plurality of eyes mounted on the bar, a rod slidably through the said eyes, links connecting one end of the rod to the blade, an offset extension formed on the opposite end of the rod, a lever pivoted adjacent one extremity of the bar, the offset extremity of the rod being hinged to the intermediate portion of the lever and actuated thereby.

In testimony whereof I affix my signature.

AMOS B. GARRETT.
